UNITED STATES PATENT OFFICE.

WILLIAM H. KENDALL, OF MONSON, MASSACHUSETTS, ASSIGNOR TO SARAH FRANCES KENDALL, OF MONSON, MASSACHUSETTS.

MACHINE FOR BLOCKING AND PRESSING HATS.

1,343,185.

Specification of Letters Patent.

Patented June 8, 1920.

Application filed April 11, 1919. Serial No. 289,356.

To all whom it may concern:

Be it known that I, WILLIAM H. KENDALL, a citizen of the United States, residing at Monson, in the county of Hampden and 5 State of Massachusetts, have invented new and useful Improvements in Machines for Blocking and Pressing Hats, of which the following is a specification.

This invention relates to a machine for 10 blocking and pressing hats in which a hood or dome coacts with a hollow block made to support a perforated hat mold, and a membrane carried by the block assumes the shape of a hat in the mold by means of air pressure in the hood. The invention is designed 15 to include means for exhausting the air from the hood and hollow block so that the elastic membrane will gradually assume the shape of the mold and fracture or breakage by a 20 sudden strain is obviated.

An object of the invention is to provide the joints between the hood and hollow block mold with a pneumatic cushion for eliminating escape of air and means for simultaneously forcing air into the hood while inflating the cushion.

A further object of the invention is to provide the hood with readily manipulative clamping means for locking the hood to the 30 block so that the air pressure in the pneumatic cushion cannot open the joints or force the members apart.

The novel features of the invention are more fully described in the following specification and claims and illustrated in the 35 accompanying drawing, in which:—

Figure 1 represents a vertical section of a machine embodying this invention.

Fig. 2 is a horizontal section taken along 40 the line 2—2 of the same.

Fig. 3 is a detail section of a cock.

Fig. 4 is a similar section showing the cock in a different position.

In the drawing the numeral 6 designates 45 a frame which is preferably formed of angular uprights. A pair of vertically arranged rods 7 are slidably mounted in the frame, a cross head 8 is secured to the upper portions of the rods and a bar 9 to the lower 50 ends of the same. Between the rods and rigidly suspended from the cross-head is fixed a dome or hood 10 of conical shape. A rod 11 pivoted to the bar can be actuated by a treadle as is well known to elevate or 55 lower the hood.

Secured to the frame is a table 12 having parallel tracks 13 located on the table. A hollow block 14 is arranged to slide or travel on the tracks and a lug 15 fastened to the table, see Fig. 2, coacts with the rear of the block to form a stop for alining the block with the hood. Supported on the block is a perforated mold or die 16 shaped to conform to the outline of a hat or similar head covering. On the block is removably 65 mounted an elastic membrane or diaphragm 17 which when depressed by air above it will force itself into the hat.

Steam or other heating medium is admitted into the block by means of a pipe 18 controlled by a valve 19 and a branch pipe 20 governed by a valve 21 is adapted to relieve or exhaust the pressure in the block when desired.

Air is admitted into the hood by means of 75 a pipe 22 controlled by a three-way cock 23 and at the same time air is passed by a branch pipe 24 into a pneumatic annular cushion 25 placed in annular grooves between the hood and block. An indicator 26 connected to the top of the hood denotes 80 the pressure in the block and cushion. The air can be exhausted from the hood by actuating the said cock 23 as indicated in Fig. 3 thereby opening an outlet 27 communicating 85 with the hood. When it is desired to introduce air into the cushion and hood the cock is positioned as shown in Fig. 4 with the inlet opened and the exhaust closed.

The clamping arrangement for locking 90 the block and hood consists of an annular member 28 supported on a flange of the hood. The member has secured to it a series of dependent clamps 29 having hooks to engage the hollow block. By rotating the 95 member the hooks are made to register or aline with slots 30 formed in the circumference of the block and the hood can be raised.

When the hood is clamped down on the 100 block the steam is admitted to heat the block and moisten the hat. The steam is then exhausted by closing the valve 19 and opening the valve 21. Air is then admitted into the hood to compress the membrane into 105 the mold and after being compressed a certain time the air is exhausted by operating the three-way cock. It will be noticed that the air is forced into the hood and at the same time into the cushion thus giving equal 110

pressure. By drawing the steam from the block and the air from the hood a vacuum is created above and below the membrane to partly collapse it onto the mold before the air is introduced into the hood. The cushion when under suitable air pressure will effectively seal the joints between the hood and the block so that none of the air or steam in the hood can escape.

10 I claim:—

1. In a hat pressing machine the combination with a lower block member, and a hood movably coacting with the block, of a pneumatic cushion arranged between the block and the hood, and means for inflating the cushion.

2. In a hat pressing machine the combination with a lower block member, and a hood movably coacting with the block, of a pneumatic cushion arranged between the block and the hood, and means connected to the hood for inflating the cushion.

3. In a hat pressing machine the combination with a lower block member and a hood movably coacting with the block, a mold supported on the block, an elastic membrane made to engage the mold, of a pneumatic cushion arranged between the block and hood, and means for inflating the cushion and simultaneously forcing air into the hood to depress the membrane.

4. In a hat pressing machine the combination with a lower block member, and a hood movably coacting with the block, a mold

supported on the block, an elastic membrane 35 made to engage the mold, of a pneumatic cushion arranged between the block and hood, means including a three-way cock for inflating the cushion and simultaneously forcing air into the hood to depress the 40 membrane, and means controlled by the cock for exhausting air from the hood.

5. A hat pressing machine comprising a lower hollow block, a perforated mold supported on the block, a movable hood coact- 45 ing with the block, an elastic membrane made to engage the mold, a steam inlet connected to the block, a branch exhaust leading to the inlet, means for admitting air into the hood, and means controlled by the air in- 50 let for exhausting the air.

6. A hat pressing machine comprising a lower block member, a hood movably coacting with the block, a pneumatic cushion arranged between the block and hood, an annular movable clamp member mounted on the hood to engage the block, and slots disposed in the periphery of the block to at 55 times register with the clamps for releasing the hood.

In testimony whereof I have hereunto set my hand in the presence of two subscribing witnesses.

WILLIAM H. KENDALL.
